DEFROSTER

John Glen Edwards, Bradley, Ark.

Application October 23, 1933, Serial No. 694,865

4 Claims. (Cl. 62—1)

This invention aims to provide a simple means for catching the water, and the ice which sloughs off, during the defrosting of the refrigerating unit of a mechanical refrigerator.

5 A preferred form has been shown, but a mechanic working within the scope of what is claimed may make changes without departing from the spirit of the invention.

Figure 1 shows in elevation, a refrigerator to 10 which the defroster has been applied.

Figure 2 is a transverse section of the defroster, in place.

Figure 3 is a perspective view of the defroster.

Mechanical refrigerators are of widely divergent constructions, but in Figure 1 there is shown 15 a refrigerator comprising a body 1 provided with a door 2, there being a compartment 3 in the body. The body 1 may contain a shelf 4, above which is located the refrigerating unit 5.

20 The refrigerating unit 5 is supported in a variety of ways, sometimes by brackets 6, connected to the top portion of the body 1. One of the pans of the refrigerating unit 5 is shown at 7.

In carrying out the invention, there is provided 25 a cover or sack 8, made of any flexible and waterproof material. Various grades of oil cloth are suggested, but not insisted upon. The cover 8 should be of a size to receive the refrigerating unit 5 amply, and may be deep enough to rest on 30 the shelf 4. Since refrigerators and their refrigerating units differ much in construction, it is obvious that large latitude is desired as to the form and size of the cover 8.

The cover 8 comprises sides 9, a bottom 10, a 35 front 11, a back 12, and a top 15. The sides 9 and the bottom 10 may be made in one piece, the front 11 and the back 12 may be joined to the sides 9 and the bottom 10 by seams and reinforcements 14, and the top 15 may be joined to the 40 sides 9 and to the front 11 and the back 12 by seams and reinforcements 23. The manufacturer can use considerable discretion as to the particular way in which the sack 8 is made.

The top 15 is divided along a median longitudinal line to form flaps 16, connected by a 45 fastening means of any desired sort. A well-known commercial fastener, which can be identified by the showing of the drawings, 17 has been shown for that purpose, but something else might be used. The fastener 17 extends a little way down on the back 12, as shown at 18, and the back, therefore, can be opened slightly, near to its upper edge. A reinforcement 19 on the inside 50 of the back 12 connects the extension 18 of the fastener 17 with the back.

The front 11 is slit downwardly from its upper edge, to form flaps 20, connected by a fastening means, of the sort hereinbefore alluded to, though some other device might be used. A reinforcement 22 on the outside of the front 11 connects 5 the lower end of the fastener 21, or its equivalent, with the front.

Hot water may be placed in the pan 1, to hasten the defrosting, the cover 8 is placed about the refrigerating unit 5, and the cover is closed at 10 the front by the fastening device 21, the cover being closed at the top by the fastening device 17 as much as the supports 6 for the refrigerating unit 5 will permit. The current is turned off the unit. The refrigerating unit 5 voids itself of ice 15 or frost, and the resulting water is caught in the cover or sack 8, that article generally being supported on the shelf 4.

When the defrosting is completed, the operator does not have a refrigerator smeared internally 20 with drip, and with its contents moved out of place to avoid the drip and to make room for a drip pan. The contents of the compartment 3 remain in their original places, dry and clean, the water melted off the refrigerating unit 5 being confined to the sack 8, which may be removed 25 and emptied.

Since the sack 8 is flexible it may be fitted about the unit 5 to clear any article on the shelf 4 or elsewhere in the refrigerator. 30

What is claimed is:

1. Means for defrosting the refrigerating unit of a refrigerator, and for collecting the water produced during the defrosting operation, when the temperature of the refrigerating unit is 35 raised, said means comprising a flexible, waterproof sack, shaped to receive the refrigerating unit and conforming approximately to the outline thereof, means for closing the sack about the refrigerating unit, and means for heating 40 the surface of the refrigerating unit, the last-specified means operating within the sack.

2. Means for defrosting the refrigerator unit of a refrigerator, and for collecting the water produced during the defrosting operation, when 45 the temperature of the refrigerating unit is raised, said means comprising a flexible, waterproof sack, shaped to receive the refrigerating unit and conforming approximately to the outline thereof, means for closing the sack about the refrigerating unit, and means for heating the surface of the refrigerating unit, the last-specified means operating within the sack, the sack being long enough to rest on a part of the refrigerator below the refrigerating unit, where- 50 55

by the weight of the load of water in the sack may be carried by said part.

3. In the process of defrosting the refrigerating unit of a refrigerator, those steps which comprise enclosing the refrigerating unit temporarily in a waterproof casing, closing the casing, heating the space within the casing to the point of defrosting, collecting in the casing the water produced during defrosting, and removing the 5 casing with the water in it.

10 4. A device for defrosting the refrigerating

unit of a refrigerator, comprising a waterproof casing shaped to enclose the refrigerating unit, means for heating the space within the casing to the point of defrosting, the casing constituting a collector for the water produced during defrosting, and means for closing the casing during defrosting, and for opening the casing after defrosting, whereby the enclosing of the casing is temporary and whereby the casing may be removed with the water in it.
